Primary Examiner — Katie Jane Stofko*(74) Attorney, Agent, or Firm* — Hartman Global IP Law; Gary M. Hartman; Domenica N. S. Hartman(57) **CLAIM**

The ornamental design for a food product, as shown and described.

DESCRIPTION

FIG. 1 is a top, left perspective view of a food product showing my new design;

FIG. 2 is a rear elevation view thereof;

FIG. 3 is a cross-sectional view thereof, taken along line 3-3 in FIG. 4;

FIG. 4 is a top plan view thereof;

FIG. 5 is a front elevation view thereof; and,

FIG. 6 is a bottom plan view thereof.

The evenly-spaced broken lines in FIGS. 1-6 illustrate portions of the food product that form no part of the claimed design. The dash-dot-dash broken lines in FIGS. 1-6 illustrate the boundary of the claimed design which forms no part thereof.
